TOOL FOR APPLYING ARMOR TO TRANSMISSION LINE CONDUCTORS

Lowell J. Kerby, Owosso, Mich., assignor to A. B. Chance Company, Centralia, Mo., a corporation of Missouri

Application September 24, 1941, Serial No. 412,129

16 Claims. (Cl. 140—149)

The present invention relates to tools for applying armor to transmission line conductors, and is particularly concerned with the provision of tools by means of which armor of a simple and effective type can be applied with perfect safety to the transmission line conductors while they are energized with high voltage current.

One of the objects of the invention is the provision of improved tools by means of which ordinary round wires may be applied to transmission line conductors in such manner that the wires are spirally twisted around the conductors and permanently secured thereto to form a coating of armor to protect the conductors against abrasion.

Another object of the invention is the provision of an armor applying device of the class described which is adapted to be manipulated by means of tools carried at the end of long insulating poles so that the armor may be applied without deenergizing the line.

Another object of the invention is the provision of a device of the class described which is simple, capable of economical manufacture and sale, sturdy, and which is adapted to apply the armor in such manner that it is firmly attached to the conductor and completely covers the conductor over the desired length of conductor.

Another object of the invention is the provision of an improved apparatus of the class described which is light, compact, capable of being carried in a tool box, and used in connection with insulating poles of the type used with various types of hot wire clamps.

Another object of the invention is the provision of an improved device for applying armor to high tension wires which is adapted to be manipulated in a very simple way so that it does not require special skill on the part of the operators, and so that the technique may be learned very quickly and easily by those skilled in the particular art to which these tools pertain.

Other objects and advantages of the invention will be apparent from the following description and drawing, in which similar characters of reference refer to similar parts throughout the several views.

Referring to the single sheet of drawings accompanying this specification;

Fig. 1 is an elevational view of a transmission line conductor showing the tools constructed according to the present invention in the course of the application of armor to the conductor;

Fig. 2 is a side elevational view showing one of the twister heads in its closed position with one of the driving tools hanging on its sub;

Fig. 3 is a front elevational view of one of the twister heads with two of the driving tools partially broken away to show the internal construction;

5 Fig. 4 is another side elevational view of a twister head as it appears when it is opened for application to the line, the head being carried by one of the standard forms of clamp stick which is applicable to the support of hot wire clamps or other members having an eye;

10 Fig. 5 is a fragmentary sectional view taken on the plane on a line passing through the axis of the twister head;

Fig. 6 is a fragmentary sectional view taken on 15 the plane of the line 6—6 of Fig. 4;

Fig. 7 is a fragmentary sectional view taken on the line 7—7 of Fig. 4 and looking in the direction of the arrows; and

Fig. 8 is a transverse sectional view taken on 20 the plane of the line 8—8 of Fig. 4.

Referring to Fig. 1, 10 and 11 indicate two twister head assemblies shown in connection with the driving and holding tools in the course of the application of armor 12 to a transmission line conductor 13. The driving and actuating tools are all identical in construction, and are merely indicated by different numerals for the purpose of designating their location. These tools are indicated by the numerals 14, 15, 16, and 17. 25 Each of these tools, which is capable of both driving the twister heads or holding the twister heads, and each of which alternately performs these different functions, preferably comprises the long inserting wooden pole 18, a universal clamping head 19, and a tool extension 20.

The poles 18 comprise elongated wooden members preferably cylindrical in shape of thoroughly dry lumber, preferably insulated with an insulating varnish. At their other ends they support the cast iron universal fitting comprising a cylindrical socket member secured by means of

30 one or more transverse metal rivet pins to the pole 18. The cylindrical socket member has an axially extending supporting flange 21 provided with a threaded bore for receiving a thumb screw or wing bolt 22. The flange 21 is usually provided with laterally projecting lugs separated by grooves for engaging the complementary lugs and grooves 23, 24 on the supporting flange 35 25 of the tool fixtures 20.

40 It should be understood that poles may be provided in which the tool fixture 20 is directly attached to the wooden pole 18 by means of a socket 19 similar to that just described.

45 50 55 The universal pole just described is itself not

new, as such poles are already in use for supporting all kinds of line tools when used on high transmission lines. The tool fixture 20 of the present invention comprises a cast metal member which has its lower end provided with the relatively flat supporting flange 25 having the lugs 23 projecting from its face 26 and separated by grooves 24. Since the clamping screw 22 is usually permanently attached to the universal pole 18, the flange 25 has an axially extending groove 27 for receiving the screw bolt 22 so that the tool fixture can be secured to the universal pole 18 by means of the clamping screw 22. These tool fixtures can, of course, be secured at any of a plurality of different angles depending upon whether it is desirable or convenient to have the tool project from the pole at an angle. The operators of these poles may, of course, be standing upon platforms, or they may be perched on the side of a line pole, so that it is often necessary to manipulate the tools in a precarious or inconvenient position.

Each of the tool fixtures 20 is preferably provided above the supporting flange 25 with an enlargement 28 comprising a substantially rectangular block portion of metal which preferably has flat sides 29 and 30 for engaging the driving pins 31 carried by the twister heads 10 or 11. The end portions 32, 33 of these blocks may also be flat, so that they can be brought into their engagement with the sides of the twister head where they will intercept the pins 31 either for holding or driving the twister heads.

Above the driving blocks 28 the tool fixtures 20 may be provided with a rod-like extension 34 which is laterally curved at 35 by a bend which brings the shank 34 into a radial position with respect to the twister head when the tool is on the head. The rest of the upper portion 36 of the tool fixture is formed into a half-circular hook portion adapted to serve as a bearing for rotatably supporting the tool on one of the hubs 37 or 38 of the twister head. This hook portion preferably extends over substantially 180° of the circumference of the hub, or slightly less than 180°, the rest of the hook being open throughout the remaining 180° or more, so that the hook can be placed on the hub through the opening of the hook. The hook is also preferably circular in form so that it has a firm engagement on the hubs 37 and 38 and is retained on the hub by gravity particularly when the tool fixture is carried by the end of a long pole depending from the hook.

Four of the tools 14-17 are required for the manipulation of the twister heads in the installation of armor to the transmission line conductor under ordinary conditions, but it is possible to utilize one twister head by clamping a band about the wires to secure one of the ends of each wire to the conductor while the wires are twisted from the other end. The twister heads 10 and 11 are identical in construction and arrangement, and two of them are preferably used in the operation of the device, although one might be used alone as just described.

Each of these twister heads comprises a metal member formed of two halves which together form a wheel adapted to be rotatably mounted on a transmission line conductor. The two halves, 40 and 41, are similar in construction, as follows:

Each comprises a centrally located half hub portion 37 and 38 projecting from each side, the hub portion being half-cylindrical, and each being

provided with a half annular retaining flange 42, 43. The hub portions 37 and 38 are formed with half cylindrical grooves 44 so that when the two halves 40 and 41 of the twister head are secured together, as shown in Fig. 2, there is a cylindrical bore extending into each end of each hub portion, as indicated at 45, 46 in Fig. 5. The bores 45, 46 are, however, separated by two inwardly extending half circular flanges 47, 48, which are each provided with a half cylindrical groove so that when they are together they form a cylindrical bore 49 for receiving a conductor wire 13. The bore 49 serves as a bearing for rotatably supporting the wheel or twister head on the conductor wire in the application of the armor. The wheel rotates and slides on the wire by means of the bearing 49. The flanges 47, 48 are also provided with a multiplicity of small cylindrical apertures 50 regularly spaced from each other and located near the periphery of the flanges 47, 48, that is, near the wall of the holes 45, 46. The apertures 50 are of suitable size to slidably receive the armor wires 51 (Fig. 1) which are used to make the armor that is applied to the conductor 13. Any desired number of apertures 50 and armor wires can be employed. The present invention has four apertures in each half hub member, and it is adapted to utilize eight wires in applying armor to one size of transmission line conductor.

It should be understood that any desired number of wire apertures and apertures of any size may be used, the number and size of apertures depending upon the size of the armor wires in relation to the conductor in which the armor is to be applied.

In effect the flanges 47, 48 serve as a guiding member for guiding the armor wires as they are being twisted about the conductor 13.

The guiding member 47, 48 has its apertures provided with a predetermined clearance with respect to the armor wires, so that when the armor wires are being twisted they are adapted to slide through the apertures and twist into spiral engagement with the conductor 13.

The friction involved in the withdrawal of the wires from the apertures 50 as they are being fed into spiral engagement with the wire is such as to insure the spiral engagement of one wire with an adjacent wire so that the conductor is completely covered with the armor thus applied.

The hub portions 37, 38 of each twister head support a relatively thin spoke flange 51', which is circular in shape and which at its outer ends supports the circular rim 52 of the wheel or twister head.

Naturally each of the flanges 51' and rim 52 of the half heads 40, 41 only form half of the wheel. Each of the rims 52 is provided with a plurality of axially projecting pins 53-58, and the pins are provided on both sides of the rim, as shown in Fig. 3. The pins 53 are preferably cylindrical in shape and may form an integral part of the rim, but in further embodiments of the invention they may comprise pins secured in bores in the rim by tight frictional fit. The pins 53 project axially from the rim 52 sufficiently so that they have firm engagement with the flat sides 29 and 30 of the driving blocks 28 carried by the tool fixture 20. However, the hook 36 is adapted to be swung laterally of the hub 37 or 38 into such angular position that the driving block 28 of any hook may engage the sides of the pins 53-58. For this purpose the flange 75 42 or 43 has a suitable clearance on each side

of the hook portion 36. The rim 52 may have its outer surface 59 cylindrical, but it is not necessarily so. The two side surfaces 60 and 61 of the rim are preferably flat, so that the driving blocks 28 on the tools 20 may be brought into flat engagement with the side of the wheel to assure the driving engagement between the flat surfaces 29 or 30 of a block with any of the pins 53-58. The two half portions 40, 41 of the twister head are different in the following respects: the upper half portion 40 is preferably provided with a flange 63 projecting radially from the rim 52 adjacent the straight border 64 of this half head 40 for engagement with a pintle 65.

The lower half 41 of the twister head 10 or 11 preferably has its rim 52 provided with a pair of radially extending flanges 66, 67 located to receive the flange 63 between them and also provided with the registering apertures for receiving a pintle 65. The pintle 65 may be a bolt, but is preferably a rivet so that the two halves of the twister head cannot come apart under any conditions. The lower twister half 41 has its flange 66 provided with a relatively thicker portion 68, which is preferably of the same thickness as the rim 52, but which projects inwardly to provide sufficient body so that a bore 69 may extend through the enlargement 68. The bore 69 is preferably located so that the rod 70 which it is adapted to slidably receive has its eye shaped end 71 located at one side of the web 51'. The eye 71 is secured to the web 51' by a rivet 72 passing through the eye 71 and web 51'. The bore 69 has a suitable clearance surrounding the rod 70 so that as the two halves 40 and 41 of the twister head pivot apart to the position shown in Fig. 4, the necessary angular movement between the rod 70 and the walls of the bore 69 is permitted. The lower end of the rod 70 is provided with a threaded portion 73, which is located outside the flat thrust surface 74 on the rim of the lower half 41. This threaded portion threadedly supports an eye member 75 having an eye 76 of the same size as the eye screw on a standard hot wire clamp so that the eye may be engaged by a standard clamp stick. The eye member 75 may have a cylindrical shank 77 provided with the threaded bore 78 for receiving the end of the rod 70. The shank 77 is also preferably provided with a transversely extending lug or pin 79 which projects from the shank at each side in such manner as to be engaged in the transverse slot which is located in the end of the standard clamp sticks of the type shown in Figs. 4 and 8.

The clamp sticks in question are preferably of the type having a long pole of wood or other insulating material for supporting a clamp stick head 80. The clamp stick head preferably has a cruciform aperture at the top for slidably supporting a cross head with a pair of pivoted jaws which are adapted to engage in the eye 76 to secure the eye to the stick. The clamp stick also has a wooden actuating member adapted to draw the cross head and jaws of the hook engaging the eye 76 downwardly into the socket of the stick until the transverse lug 79 engages the sides of the cruciform socket above mentioned.

Thus the eye member 75 may be fixedly secured to the end of a clamp stick so that both of the twister heads 10 and 11 may be supported by clamp sticks and applied to the armor.

The operation of the clamp stick on a twister head is as follows: The jaws of the clamp stick may be engaged in the eye 76, and then the jaws may be drawn downwardly into the socket of the clamp stick to draw the eye 76 into the socket.

This will bring the bar 79 into the cruciform part of the socket of the clamp stick so that the eye member 75 will be fixedly held by the upper end of the clamp stick.

10 As the clamp stick is rotated while the twister head 10 or 11 is held in the same plane, the threaded member 75 will move on the threaded portion 73 of the rod 70.

15 A clockwise rotation of the clamp stick will draw the two halves of the twister head together from the position of Fig. 4 to that of Fig. 2. A counter-clockwise rotation of the clamp stick will cause the threaded member 75 to recede downwardly on the rod 70. This will cause the

20 upper half 40 to be held in the same position by the clamp stick, threaded member 75 and rod 70, but the lower half 41, having its thrust surface 74 resting on threaded member 77, will drop to the position of Fig. 4. Thus it will be evident

25 that the clamp stick may be used to lift the twister head up to place it on a wire or transmission line conductor where the stick can be used to close the head or to open it. The clamp stick must, of course, be removed when the head is to be rotated.

The method of application of the armor to the wire and the mode of manipulation of the foregoing tools to accomplish this result is done as follows:

35 The two twister heads are opened to the position of Fig. 4. Clamp sticks of the type described having a hook engaging the eye 76, or having two clamping jaws engaging in the eye, are fixedly secured to the eye member 75 of each twister head, with the transverse lugs 79 in the slots at the end of the clamp stick.

The twister heads are then placed in parallel position about a foot apart and armor wires are inserted in the apertures 50 in such manner that the ends of the wire project beyond the twister heads an equal amount in each direction. With all of the apertures 50 filled with armor wires and the twister heads open as in Fig. 4 and carried by clamp sticks, two operators may then apply the twister heads simultaneously to the conductor wire 13. This is done by lifting the assembly by means of the two clamping sticks and placing the upper slots 49 for the conductor wire 13 on the conductor wire 13. Then the clamp sticks are rotated in the clockwise direction, as previously described, until the two halves of the twister heads are both drawn tightly together to the position of Fig. 2.

60 The clamp sticks may then be removed in the usual way leaving the twister heads on the conductor 13 with the armor wires.

Four of the tools 20 comprising the hook members illustrated in Figs. 2 and 3 are then applied to the hubs 37, 38 of the two twister members as shown in Fig. 1. These tools are indicated in Fig. 1 by the numerals 14-17. The handles of these tools are long wooden poles, and each tool on each twister head serves alternately for holding and next for twisting the head.

70 Two operators are preferably required and they operate the twister heads 10 and 11 to rotate them simultaneously in opposite directions. The twister heads may be rotated in either direction, 75 provided the relative rotation is opposite.

For example, in Fig. 1 the twister head 11 has been rotated counterclockwise, viewing from the left, and the twister head 10 has been rotated clockwise, viewing it from the left. This rotation is accomplished as follows:

With the tool 14 in the position of Fig. 1, the tool 15 may be pivoted laterally, that is longitudinally of the line, at its lower end, until the driving block 28 is out of engagement with the pin 55 or 56. Then the tool 15 may be pivoted upon the hub 38 with the wire 13 serving as an axis until it is in position to engage behind the lug 55, for example. The operator may then pull the rod rotatively about the conductor wire as an axis in a clockwise direction in Fig. 2, the driving block 28 engaging the lug 55 to rotate the twister head 11.

In the meantime the operator may be moving the stick 14 laterally to clear the next pin, so that stick 14 may be moved backwardly behind the next pin on that side of the twister head until the driving block 28 on that stick can engage behind that pin. The next step is the rotation of the twister head 11 further in the same direction by means of the stick 14, having its driving block 28 engaging the pin while the operator is moving the stick 15 laterally and back to take a new bite on a pin on that side of the wheel. Thus the tools may be said to operate in a manner like ratchets, one holding and advancing the wheel while the other is taking a new bite, and the operators may rotate the two twister heads in opposite directions to place the armor wire as shown at 12 in Fig. 1. As this is done the twister heads are moved longitudinally of the conductor wire 13, and they feed out the armor wire until the twister head passes off the end of the armor wires. Then the ends of the armor wires may be ironed down by delivering an ordinary tap clamp and rotating it, or they may be cut off by using a snipping tool on the end of a long pole.

My method of applying armor may be briefly summarized as follows:

A plurality of armor wires are simultaneously supported about the conductor wire in parallel position equally spaced from each other circumferentially of the conductor wire. The armor wires are then engaged simultaneously at two spaced points and twisted spirally by rotation of the end portions of the armor wires in opposite directions, the points of engagement with the armor wires receding from each other as the wires are spirally applied to the conductor. The armor wires are thus spirally wrapped in edge-wise engagement with each other upon the conductor outwardly toward both ends of the armor wires, and the armor wires have their ends cut off if necessary and ironed down by means of the application of an ironing force with a hot wire clamp or other clamping member.

It will thus be observed that I have invented an improved method of delivering armor wires to high voltage conductors, and improved tools for accomplishing this result. My tools are very simple and compact, as they involve parts which may be attached to universal poles and which may be carried in any tool box. The twister heads themselves are relatively simple and compact, and may also be carried in a tool box.

It is not necessary to deenergize the line, and this service need not be interrupted. The manipulation of the tools and application of the armor may be accomplished with perfect safety as all of it may be done at the end of wooden

poles of the same length as standard clamp sticks. The armor may be very tightly twisted on the conductor, and as ordinary round wires may be used, the armor may be purchased at a lower cost than the material of the armor of the prior art, which involved the use of flat ribbons.

While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim as new and desire to secure by Letters Patent of the United States, is:

1. A tool of the class described comprising a twister head split on its longitudinal center line into individual sections hingedly connected together, a hub, a centrally disposed wire receiving opening in said hub, and a plurality of smaller openings surrounding said wire receiving opening in circumferential spaced relation, laterally projecting lugs mounted on both sides of the rim of the twister head, and grooves provided on said hub to accommodate a ratcheting tool.

2. In a tool of the class described comprising a disk-shaped head split on its longitudinal center line to form individual sections hingedly connected together at the one edge, a rim on the head, laterally projecting lugs provided thereon in spaced relation, a bored hub, grooves adjacent the opposite ends of the hub, a centrally disposed wire accommodating opening in said hub, a plurality of circumferentially arranged openings surrounding said center opening, means for securing the individual sections in closed position, and ratcheting means mounted in said grooves and engageable with said lugs for step-by-step rotation of said head.

3. In a tool of the class described comprising a twister head split on its longitudinal center line to form individual sections hingedly connected together, a rim on said head, laterally projecting lug mounted on the opposite sides of the rim in spaced relation, a centrally disposed hub, flanges on the ends of the hub and forming grooves adapted to loosely accommodate a ratcheting tool, a centrally disposed opening in said hub, circumferentially arranged openings surrounding said centrally disposed opening, and ratcheting handles loosely and rotatably mounted in the grooves on said hub and engageable with said lugs for rotating said head.

4. A tool of the class described, comprising a twister head split on its longitudinal center line to form individual sections hingedly secured together at the one edge, a rim on said head, laterally projecting pins mounted on the opposite edges thereof, with the pins on one side in staggered relation to the pins on the opposite side, a centrally disposed bored hub, grooves at the opposite ends of the hub, a relatively thin web dividing said bore in said hub into individual chambers and provided with a centrally disposed transmission line accommodating opening therein, a plurality of smaller openings arranged in circumferentially spaced relation around said centrally disposed opening, and a ratcheting tool adapted to be rotatably mounted on said hub and releasably engageable with said pins for step-by-step rotation of said head.

5. A twister head for twisting a series of armor wires on a line conductor comprising a rotatable member having a centrally located aperture for

receiving the conductor wire, whereby it is rotatably supported on the conductor wire, said member having a plurality of transverse apertures for slidably receiving armor wires, said head comprising a pair of separable parts joined along a line intersecting said first mentioned aperture and pivoted together at one side of said aperture to open the separable parts for access to the aperture, and means for controlling the position of the separable parts of said member comprising threaded means located between the aperture and the point of pivot of said parts and carried by one of said parts and acting on the other of said parts, said threaded means including an actuating member having an eye adapted to be engaged by a standard clamp stick.

6. A twister head for twisting a series of armor wires on a line conductor comprising a rotatable member having a centrally located aperture for receiving the conductor wire, whereby it is rotatably supported on the conductor wire, said member having a plurality of transverse apertures for slidably receiving armor wires, said head comprising a pair of separable parts joined along a line intersecting said first mentioned aperture and pivoted together at one side of said aperture to open the separable parts for access to the aperture, and means for controlling the position of the separable parts of said member comprising threaded means located between the aperture and the point of pivot of said parts and carried by one of said parts and acting on the other of said parts, said threaded means including an actuating member having an eye adapted to be engaged by a standard clamp stick, and said actuating member having a transverse bar carried thereby adapted to be engaged by the end of the clamp stick when the eye is withdrawn in the clamp stick to secure the actuating member fixedly to the clamp stick.

7. A twister head for twisting a series of armor wires on a line conductor comprising a rotatable member having a centrally located aperture for receiving the conductor wire, whereby it is rotatably supported on the conductor wire, said member having a plurality of transverse apertures for slidably receiving armor wires, said head comprising a pair of separable parts joined along a line intersecting said first mentioned aperture, and insulating means for supporting said head and applying it to a line conductor, said rotatable member being formed at its opposite sides with hubs and guide flanges for engaging actuating tools.

8. A twister head for twisting a series of armor wires on a line conductor comprising a rotatable member having a centrally located aperture for receiving the conductor wire, whereby it is rotatably supported on the conductor wire, said member having a plurality of transverse apertures for slidably receiving armor wires, said head comprising a pair of separable parts joined along a line intersecting said first mentioned aperture, and insulating means for supporting said head and applying it to a line conductor, said rotatable member being formed at its opposite sides with hubs and guide flanges for engaging actuating tools, and having a plurality of axially extending lugs extending from its opposite sides to engage said actuating tools.

9. A line tool for actuating twister heads comprising an elongated insulating pole and a metal tool member carried thereby at one end, said tool member being formed at its end with a partially circular hook, said hook extending over

slightly less than 180° at its inner circular element, whereby an opening is left to apply it to a cylindrical hub, said tool member having a shank provided with an enlargement having a pair of oppositely located twister engaging surfaces located on a plane at substantially right angles to the plane of said hook.

10. A line tool for actuating twister heads comprising an elongated insulating pole and a metal tool member carried thereby at one end, said tool member being formed at its end with a partially circular hook, said hook extending over slightly less than 180° at its inner circular element, whereby an opening is left to apply it to a cylindrical hub, and said metal tool member having a shank between said pole and hook provided with front and rear engaging surfaces for firm engagement with projecting lugs on a twister head.
11. A twister tool for actuating a twister head in applying armor comprising a metal member having a universal attaching flange provided with a slot for receiving a securing screw on a universal pole, said tool having a shank extending from said flange and having a partially circular hook formed on the end of said shank, said hook extending over slightly less than 180° at its inner circular element whereby it may be applied to the round hub of a twister head, said shank also having an enlargement having a pair of oppositely located twister engaging surfaces located on a plane at substantially right angles to the plane of said hook.

12. An assembly for twisting armor wires comprising a pair of twister heads rotatably mounted upon a conductor wire, each of said twister heads being formed with a plurality of apertures for passing armor wires, and each of said heads having laterally projecting hubs and laterally projecting lugs spaced from said hubs, and a pair of actuating tools carried by each of said twister heads, each tool having its end pivotally mounted on one of said hubs and holding an insulating pole, whereby the tools may be used alternately to advance the twister heads in opposite directions by the alternating engagement of said tools with said lugs in rotating each twister head.

13. An assembly for twisting armor wires comprising a pair of twister heads rotatably mounted upon a conductor wire, each of said twister heads being formed with a plurality of apertures for passing armor wires, and each of said heads having laterally projecting hubs and laterally projecting lugs spaced from said hubs, and a pair of actuating tools carried by each of said twister heads, each tool having its end pivotally mounted on one of said hubs and holding an insulating pole, whereby the tools may be used alternately to advance the twister heads to opposite directions by the alternating engagement of said tools with said lugs in rotating each twister head, said tools having partially circular hook-shaped ends and said hubs having guide flanges for retaining said hook-shaped ends on said hubs.

14. In an assembly for twisting armor wire on a conductor, the combination of a pair of rotatable wheels adapted to be rotatably mounted on the conductor in spaced relation to each other, each of said wheels having an aperture spaced radially from the conductor and adapted to receive an armor wire, manual means carried on insulating poles for rotating one wheel in one direction and rotating the other wheel in the opposite direction to effect a spiral winding of the

armor wire located in said aperture about the conductor.

15. In an assembly for twisting armor wire on a conductor, the combination of a pair of rotatable wheels adapted to be rotatably mounted on the conductor in spaced relation to each other, each of said wheels having apertures spaced radially from the conductor and adapted to receive armor wires, manual means carried on insulating poles for rotating one wheel in one direction and rotating the other wheel in the opposite direction to effect a spiral winding of the armor wires located in said apertures spaced from said conductor for applying a plurality of armor wires to the conductor.

16. In an assembly for twisting armor wire on a conductor, the combination of a pair of rotatable wheels adapted to be rotatably mounted on the conductor in spaced relation to each other, each of said wheels having an aperture spaced radially from the conductor and adapted to receive an armor wire, manual means carried on insulating poles for rotating one wheel in one direction and rotating the other wheel in the opposite direction to effect a spiral winding of the armor wire located in said apertures about the conductor, said latter means comprising a step-by-step actuating device.

LOWELL J. KERBY.
